UNITED STATES PATENT OFFICE.

WILLIAM J. BROWNE, OF GLADSTONE, MINNESOTA.

SULKY GANG-PLOW.

SPECIFICATION forming part of Letters Patent No. 501,179, dated July 11, 1893.

Application filed August 22, 1892. Serial No. 443,824. (No model.)

To all whom it may concern:

Be it known that I, WILLIAM J. BROWNE, a citizen of the United States, residing at Gladstone, in the county of Ramsey and State of Minnesota, have invented certain new and useful Improvements in Sulky Gang-Plows, of which the following is a specification.

This invention relates to sulky gang plows, and consists in the construction, combination, and arrangement of parts, as hereinafter shown and described, and specifically pointed out in the claim.

In the drawings, Figure 1 is a side elevation, and Fig. 2 is a plan view, of the beams and mold boards of a gang plow, with my improvements attached thereto. Fig. 3 is an enlarged side elevation, and Fig. 4 is an enlarged plan view, of a portion of the trailing wheel connecting mechanism, illustrating more fully

the details of the construction.

A' A² represent the mold boards, and A³ A⁴ the beams connected by the cross braces A⁵, and A⁶ the seat, all arranged in the ordinary manner.

B' is the trailing wheel journaled in a yoke frame formed of curved side pieces B² B³ connected at their upper ends to a head block or frame B⁴, and supporting the axle B⁵ of the trailing wheel in their lower ends.

Rigidly supported in a substantially upright position in the head frame B⁴ is a shaft D' having a bracket D² swiveled upon it above the frame B⁴, and also provided with an arm D³ rigidly attached to its upper end, which serves the double purpose of an arm to carry a trip latch and stop, but also as a bearing to prevent the bracket from being thrown from its seat.

Projecting backward from the swiveled bracket D² is a smaller bracket or arm D⁴ having guides a' a² through which a spring bolt D⁵ fits, the outer end of the spring bolt being enlarged and formed into a doubly inclined head b' projecting beyond the outer end of the bracket D⁴ and adapted to engage with a correspondingly doubly inclined cavity or depression b² in a rib b³ depending from the outer end of the arm D³, while the inner end of the bolt projects through the guide a' and is formed with an incline b⁴ underneath which the undercut end b⁵ of a gravity latch D⁶ piv-

oted at b⁶ in the arm D³ fits when the latch is depressed, as in Figs. 1, 2, and 3.

Projecting from the front side of the bracket D' is a wing or plate D⁷ upon which a clamp- 55 ing plate D⁸ is swiveled at d' and attached rigidly by its free end to the rear of the longer beam A³ as shown, the plate D⁸ being pivoted to the wing D⁷ so that the bracket D² and its attached trailing wheel, arms, and other parts, 60 will freely move vertically upon the pivot d'.

Pivoted at d² upon the clamp plate D⁸ is a lever D⁹ projecting upward and forward and provided with a spring pawl e' adapted to engage with segmentally arranged teeth e² upon 65 the plate D⁸, as shown. The lower end of the lever D⁹ projects downward below the line of its pivot d², and is connected by a pivoted link D¹⁰ to the lower portion of the wing D⁷, as shown.

D¹¹ is a supporting plate connecting the pivot d² and beams A³ A⁴ so as to form an additional connection between the bracket D² and the beams and also to support the pivot d² of the lever D⁹, whereby the connection between the parts is greatly strengthened and supported. By this simple arrangement if the lever D⁹ be moved downward or forward the lower end will by its connection to the bracket D² by the link D¹⁰, throw the bracket 75 D² and its attached trailing wheel upward, thus allowing the plows to cut a deeper furrow, and then *per contra* if the lever be drawn backward, the trailing wheel will be thrown downward, so that the plows will be correspondingly elevated, to either cut a more shallow furrow, or to be elevated entirely from the ground. Thus by adjusting the lever D⁹ along 80 the segmental teeth e², the shares of the plows may be set to cut any desired depth, or ele- 85 vated entirely from the ground, as may be required. When the gravity latch D⁶ is depressed with its undercut point b⁵ in the rear of the bolt D⁵, and with the doubly angular end b' in its seat in the cavity b², the arm D³ 90 will be thereby held rigidly coupled to the bracket D², and thus retain the trailing wheel B' in a fixed position in line parallel with the land sides of the plow. When forming straight furrows this will be the position in which the 95 parts will be retained, but when turning corners, or when it is desired to form short curves,

the latch D⁶ is elevated as shown in dotted lines in Fig. 3, which leaves the bolt D⁵ free to be depressed by any pressure brought to bear against its outer end. When thus arranged any side strains upon the forward ends of the beams would cause the bracket D² with its arm D⁴ to be moved to one side and thereby cause the bolt D⁵ to be compressed against the inclined edges of the cavity b², and thus release the trailing wheel and permit it to follow the curved line of the furrow. Then when the plow is again brought into a straight line the end b' of the spring bolt will snap into place in the cavity b², as before, where it may be again locked by the latch D⁶. Curved or angular guide wings b⁴ are formed upon the lip b³ to act as guides to cause the end b' of the bolt D⁵ to enter its seat b² with certainty, as well as to reduce the friction between the parts.

Having thus described my invention, what I claim as new is—

In a gang plow, the beams having the plate

D⁸ attached thereto, bracket D² pivoted vertically to said plate and having vertical shaft 25 D' journaled therein, and provided with arm D⁴ carrying spring bolt D⁵, the trailing wheel B' attached to the lower end of said shaft and adapted to be moved laterally therewith, an arm D³ upon the upper end of said shaft and 30 having depending concave lip b³ with which said spring bolt is adapted to engage, and a trip latch D⁶ pivoted in said arm D³ and adapted to lock said trip bolt in engagement with said lip, whereby a rigid coupling is capable 35 of being made between said trailing wheel frame and said beams, substantially as and for the purpose set forth.

In testimony whereof I have hereunto set my hand in the presence of two subscribing 40 witnesses.

WILLIAM J. BROWNE.
